UNITED STATES PATENT OFFICE.

UTLEY WEDGE, OF ARDMORE, PENNSYLVANIA.

METALLURGICAL FURNACE.

1,208,250.

Specification of Letters Patent. Patented Dec. 12, 1916.

Application filed March 1, 1915. Serial No. 11,332. Renewed April 27, 1916. Serial No. 94,057.

To all whom it may concern:

Be it known that I, UTLEY WEDGE, a citizen of the United States, residing in Ardmore, Pennsylvania, have invented certain improvements in Metallurgical Furnaces, of which the following is a specification.

One object of my invention is to so construct a metallurgical or like furnace that the hearths can be readily introduced into or removed from the same, and another object is to provide a simple and effective means of mounting the rabbles directly upon a hearth of the furnace. These objects I attain in the manner hereinafter set forth, reference being had to the accompanying drawings, in which—

Figure 1 is a vertical sectional view of a furnace in which my invention is embodied; Fig. 2 is a horizontal section on the line 20 *a—a*, Fig. 1; Fig. 3 is a horizontal section on the line *b—b*, Fig. 1, and Figs. 4 and 5 are sectional views on enlarged scale, illustrating means employed for supporting certain of the rabbles of the furnace.

In the drawing, I have illustrated my invention as applied to a small experimental or laboratory furnace with a central rotating shaft carrying some of the hearths of the furnace, alternating fixed hearths being mounted on the circular wall of the furnace. My invention, however, is not limited to a furnace having alternate fixed and rotating hearths but may be applied to other furnaces as well.

In Fig. 1 of the drawing, 1, 1^a represent the circular wall structure of the furnace and 2 a central rotating shaft which has, near its upper end, a worm wheel 3 rotatably mounted upon anti-friction rollers 40 at the top of the furnace, the suspended portion of this shaft carrying circular hearths 4 which alternate with fixed hearths 5 projecting inwardly from the outer wall of the furnace.

The furnace charge is first deposited upon the roof 6 of the furnace, is fed inwardly to a central opening in said roof by means of rabbles 7 carried by arms 7^a on the shaft 2, and is then fed over the successive hearths 50 of the furnace and drops from hearth to

hearth until it is finally discharged from the lowermost of said hearths.

The feeding of the charge over the hearths is effected by means of rabbles 8 depending from the roof of the furnace, by rabbles 9 55 depending from the fixed hearths, and by rabbles 10 depending from the rotating hearths, said rabbles being mounted as described hereinafter.

The wall of the furnace is provided with 60 three sets of openings, those of the first set being normally closed by means of plugs 11, those of the second set constituting peep-holes, which are preferably provided with transparent heat insulators 12 of mica or 65 other available material, and the third set being provided with the burners 14 for effecting the heating of the charge. The openings of the first set, when the plugs are removed therefrom, permit access to the 70 interior of the furnace, the openings of the second set provided for inspection of the charge in its passage through the furnace, and the burners in the openings of the third set radiate heat upon the charge during such 75 passage.

The burners are intended to use liquid or gaseous fuel and each burner consists of a casing 13 closed at its inner end by means of a plug 14 of firebrick or other porous refractory material, to the outer face of which the fuel supply has access and, being under pressure, flows through the pores of the plug and is thereby heated to such temperature that when it reaches the inner face of the 85 plug it will readily ignite and produce a flame which covers the face of the plug and radiates heat onto the charge passing through that chamber of the furnace with which the burner communicates. 90

In order to prevent overheating or ignition of the fuel in the burner casing outwardly beyond the plug 14, and thus preclude the possibility of a flareback or explosion of gas in the burner casing, I provide the latter outwardly beyond the plug 14 with a cooling device which may be variously constructed but which, in the present instance, I have shown as in the form of a hollow casing 15 which fits snugly in the 100

burner casing 13 and is provided with pipes 16 whereby a flow of water or other cooling fluid through the same may be maintained, the fuel supply pipe 17 passing through this 5 casing and supplying the fuel to a chamber 18 intervening between the forward face of said casing and the outer face of the plug 14.

The rabbles 8 are mounted upon and depend from the roof of the furnace in the 10 manner shown in Fig. 4, each of said rabbles having an enlarged head 8^a which fits into the correspondingly enlarged upper portion of a slot formed in the roof of the furnace for the passage of the rabble 8 vertically therethrough, said roof having, in the 15 rear of the rabble, a depending flange 8^b constituting a bearing for the upper portion of the rabble and serving to impart the desired rigidity thereto. The rabbles 9 and 10 20 are likewise provided with enlarged upper ends or heads 9^a (Fig. 5), confined between jaws 20 which are inserted into appropriate openings in the hearths of the furnace and extend below said hearths, the lower ends 25 of each pair of jaws having inwardly projecting ribs 21 which engage with the enlarged head of the rabble so as to properly support the same vertically. The outer faces of the jaws and the inner faces of the openings formed in the hearths for their reception flare outwardly from bottom to top so that the downward movement of each rabble carrying pair of jaws is arrested when it reaches its proper position in the hearth. 30

35 The space between the jaws above the head of the rabble may be filled with clay or cement 9^b or 10^b so as to provide a continuous upper surface on the hearth for the passage of the material under treatment but 40 when it is desired to remove a rabble this body of clay or cement can be readily dislodged by upward pressure applied to the rabble head below, or both the rabble and the carrying jaws may be removed from the 45 hearth as a unit and the body of clay or cement afterward dislodged if it is desired to remove the rabble from between the jaws.

The rotating hearths 4 are mounted upon 50 rings 22 which are fitted to reduced portions 23 of the shaft 2 and project outwardly beyond said shaft and beneath the hearths 4, as shown in Fig. 1, and between the hearths 4 the shaft 2 is surrounded by rings 24 of firebrick or other refractory material.

55 The fixed hearths 5 are mounted upon shelves 25 projecting inwardly from the outer wall of the furnace and both the fixed hearths and the rotating hearths are made in halves, as shown in Fig. 3, in order that they 60 can be readily inserted and removed from the furnace, the portion 1^a of the outer wall being, as shown in Fig. 3, removable from the portion 1 of the same for this purpose.

In like manner the rings 22 are made in halves, as shown by dotted lines in Fig. 1, 65 for convenience of application or removal, and the refractory blocks 24 may also be thus constructed, if desired.

Although I have described my invention as applied to a metallurgical furnace and 70 although it is intended mainly for use in that connection, it will be evident that the construction described and shown is also available for use in concentrating, drying, evaporating, or like apparatus, hence the 75 term "furnace" as herein used is to be construed as applying to such analogous apparatus.

I claim:

1. The combination of a rabble blade having an enlarged head with a rabble supporting member having therein a slot enlarged in its upper portion for the reception of the enlarged head on the rabble blade, said supporting member having also a rib or flange 85 extending below the rabble head and bearing upon the rear face of the rabble blade.

2. The combination of a rabble blade having an enlarged head, a hearth or like support having an opening therein, and a pair 90 of jaws carrying said rabble blade and adapted to said opening, one of said jaws having a rib for engaging the enlarged head of the rabble blade.

3. The combination of a rabble blade having an enlarged head, a hearth or like support having an opening therein, and a pair 95 of jaws carrying said rabble blade, and adapted to said opening, each of said jaws having a rib for engaging the enlarged head 100 of the rabble blade.

4. The combination of a rabble blade having an enlarged head, supporting jaws for said rabble blade, a hearth or equivalent blade support having an opening therein for 105 the reception of said jaws, and a filling body occupying the space between said jaws above the top of the rabble blade.

5. The combination of the rabble blade having an enlarged head, a hearth or equivalent blade support in which said enlarged head is mounted below the top of the same, and a filling body occupying the space in said support above the top of the rabble 110 blade.

6. A furnace having a central shaft with hearths mounted thereon, said hearths being composed of separable segments whereby said segments can be removed laterally from the shaft.

7. A furnace having a shaft, supporting rings thereon, and hearths mounted upon said rings and composed of laterally removable segments.

8. A furnace having an outer wall with 125 removable section at one side of the same,

and internal sectional hearths whose sections are laterally removable through the opening in the side wall of the furnace.

9. A circular furnace having an outer wall with removable section at one side of the same, alternating fixed and rotating hearths in said furnace, and a central shaft carrying said rotating hearths, both fixed and rotating hearths being made in sections re-

movable laterally through the opening in the 10 side wall of the furnace.

In testimony whereof, I have signed my name to this specification, in the presence of two subscribing witnesses.

UTLEY WEDGE.
